UNITED STATES PATENT OFFICE.

EZRA C. FITCH, OF MANCHESTER, MASSACHUSETTS, ASSIGNOR TO WALTHAM WATCH COMPANY, OF WALTHAM, MASSACHUSETTS, A CORPORATION OF MASSACHUSETTS.

STRAP CONNECTOR.

1,417,507.

Specification of Letters Patent. Patented May 30, 1922.

Application filed February 8, 1921. Serial No. 443,327.

To all whom it may concern:

Be it known that I, EZRA C. FITCH, a citizen of the United States, residing at Manchester, in the county of Essex and State of Massachusetts, have invented new and useful Improvements in Strap Connectors, of which the following is a specification.

The subject of the present invention is a connector intended and adapted for connecting wrist watches to the ends of a strap which is capable of being passed in the manner of a bracelet around a person's wrist for mounting the watch thereon. A strap so used is considered for the purpose of this specification as a bracelet; and any form of bracelet, whether it is specifically a strap or of other character, provided it is capable of attachment to the watch by such a connector, is equivalent to a strap within the meaning of the appended claims. However, the protection which I claim is not necessarily limited to the use or combination of the connector with a watch and a strap, except as appears from the express terms of the claims, for it is also applicable to attaching a buckle to a strap, as explained in the following specification, and it may have other uses as well. Wherefore I claim the connector having the characteristics hereinafter defined as my invention in all uses and combinations for which it may be available.

The main object of the invention is to provide a connector in the nature of a hinge pin which can be easily applied to and removed from the objects to be connected, has means in itself for insuring against accidental dismounting, and is inexpensive to manufacture. For the particular use of connecting a strap end to a watch, or a buckle, my object further includes that of enabling a closed loop in the end of a strap to be made fast between lugs on the watch case or buckle securely, easily, and rapidly. Referring to the drawing in which the preferred form of the invention is disclosed,

Figure 1 is a view of the watch and parts of a strap bracelet extended.

Figure 2 is an elevation of the same as seen from beneath Figure 1.

Figure 3 is a sectional view in detail and on an enlarged scale of the connector in its association with the watch case and the strap.

Figures 4 and 5 are detail elevations of the parts of the connector separated from one another.

Figure 6 is a diagram representing in an exaggerated way the coaction of the two parts of the connector in preventing dismemberment. In this figure the lateral dimension of the connector has been enlarged out of proportion to the longitudinal dimension in order that the locking effect may be clearly illustrated.

Figures 7 and 8 are views corresponding to Figures 4 and 5 illustrating a modified form of the invention.

Like reference characters designate the same parts in all the figures.

a represents a watch of any make, style, and design suitable to be worn upon the wrist of the possessor, and *b* and *c* are two straps forming parts of a bracelet, the strap *b* having a buckle *d* with which the end of the strap *c* may be engaged. These straps are shown as being of leather, but they may be made of webbing or of any other material suitable for a bracelet. The material of each strap at the end which is intended to be attached to the watch is fashioned into a closed loop or eye *e*, and each loop or eye is placed close to the side of the watch case between two lugs *f*, *f* which project from the case center *g*. For the purpose here indicated there are two pairs of lugs *f* each of which pairs is at the opposite side of the watch case from the other. Except that lugs substantially equivalent to those here shown (or at least one pair of such lugs) are practically essential, the watch may otherwise have any design and be of any size which suits the taste of the possessor.

For connecting each strap end to the embracing lugs I provide a tube *h* of a diameter adapting it to enter the loop or eye of the strap, and of a length permitting it to pass between the lugs of one pair, and a locking pin *k* having a diameter enough less than the bore of the tube to permit of its being easily inserted therein, and a length greater than the space between the two lugs of one pair, but preferably no greater than the distance between the outer surfaces of such lugs. Alined holes large enough to permit easy passage through them of the pin are provided in the lugs. The pin is bent between

its ends, preferably at or near the middle and on a curve wide enough to avoid sharp bending at any point; and the extent of bending is such that the middle part of the 5 pin is offset from a straight line between its ends more than the difference between the diameter of the pin and the bore of the tube. In proportion to the length and diameter of the pin, the extent of bending indicated by 10 Figure 5 is sufficient for my purposes.

When the tube is inserted between the lugs of the watch case and the pin is passed through the lugs and the intermediate tube so that its ends enter both lugs, such ends 15 form pivots which connect the strap to the watch case and permit angular movement of the strap about the line of the pivots. Then that part of the pin which occupies the tube is deflected from its unstressed condition and, owing to its resiliency, it exerts 20 pressure in one direction against one side of the tube at or near its ends and in the opposite direction against the opposite side of the tube at or near its middle. The pressure so exerted produces a frictional clutching 25 effect which prevents accidental slipping of the pin from the tube; and the tube, being confined between the lugs, prevents either pivot end of the pin from leaving the 30 hole which it occupies in the adjacent lug.

The clutching effect last described is indicated in Figure 3, but is more fully illustrated in the diagrammatic Figure 6. Here the disproportionately enlarged diameters 35 of the pin and tube show the divergence between the line of the pin and the line of the tube bore with the contact at the points 1 and 2 between the pin and inner walls of the tube at one side, and at 3 on the other 40 side. To attain the desired effect, the pin in its normal unstressed condition should extend in a line so far different from the line of the tube bore that it is deflected from this normal shape and put under stress by 45 its engagement with the inner walls of the tube. The pin therefore must have sufficient elasticity and resilience to be thus deflected within its elastic limit. It must also be stiff enough to be inserted by an endwise 50 thrust through the lugs and tube against the resistance offered by this frictional contact, and enough strength resistant to shearing and bending to serve the purposes of a connector in the uses to which it is put. 55 For the specific use here illustrated and described hard metallic wire has the necessary qualities here outlined. Steel, brass, and gold are all suitable metals or alloys of which wire for the purposes indicated may 60 be made, and they are named to indicate in a general way what characteristics are necessary and sufficient. Drawn wire or rolled rods of various diameters may be used according to the service required in any particular case.

The invention is not limited to a straight tube and bent pin, for a bent or curved tube *h'* and a straight pin *k'* as shown in Figures 7 and 8 may be used with equivalent effect; and a curved or bent pin may be combined with a curved or bent tube, provided the divergence between the line of the pin and the line of the bore of the tube is great enough to cause the clutching effect already described. The curved form of tube may 75 be preferable for some purposes to the straight tube for connecting a strap to a watch case having a curved perimeter, as by 80 its use the strap end may be conformed closely to the curvature of the case, when the strap is of sufficiently flexible material.

Essentially the same connector is employed to attach the frame of the buckle *d* to the opposite end of the strap *b* from that which is connected to the watch. The buckle 85 frame then is provided with apertured ends or ears *d'* *d''* which embrace the ends of a closed loop *e'* in the adjacent strap end; and a tube essentially like the tube *h* or *h'* is placed in this loop and between the buckle 90 frame ends, while a pin, essentially like the pin *k*, or *k'*, respectively, is passed through the buckle frame ends and the tube embraced by them.

It will be readily apparent that the connector or connecting means here disclosed can be easily placed in or removed from the position of use, and is at the same time well secured against accidental disassociation of 95 its members. Evidently also the connector 100 is producible at low cost.

What I claim and desire to secure by Letters Patent is:

1. The combination of a member having lugs spaced apart, with a second member 105 having a loop or eye in its end adapted to enter between such lugs, a tube occupying said eye, and a pin passing through said tube and into the lugs and being of springy material and offset between its ends to an 110 extent which causes it to be clutched by the ends and intermediate part of the tube.

2. The combination of two separable elements, one of which has lugs embracing the other, and such lugs and the element 115 embraced thereby contain an aligned passage, with a connector occupying such passage and extending therefrom at opposite ends into the lugs, and being so bent between its ends that it is distorted from its normal shape 120 by, and engaged frictionally on opposite sides with, the walls of the passage in the embraced element.

3. The combination of two separable elements, one of which has parts embracing a 125 part of the other and such parts contain an interior continuous passage, of a connecting pin enough smaller in diameter than said passage to be capable of insertion endwise into, and removal from, the passage; said 130

- pin being of metal having such elasticity and resilience that it may be bent within its limit of elasticity to a distance greater than the difference between its diameter and the 5 diameter of the passage, and the pin in its normal unstressed condition being formed in a line dissimilar to the line of the passage, whereby it is distorted when located in the passage and caused to exert frictional 10 clutching pressure in opposite directions on different parts of the passage.
4. The combination with a member having spaced apart lugs with alined holes in them, of a tube substantially as long as the 15 space between said lugs, and a pin adapted to occupy the bore of said tube and to project at its ends therefrom into the holes of said lugs; the pin being enough smaller in diameter than the bore of the tube, and stiff 20 enough, to be passed endwise through the lugs and tube by pressure applied to its end, and being resilient enough to bend between its ends within the elastic limit, and the line of the pin when in its unstressed condition 25 being enough different from the line of the said bore to cause application of a frictional clutching pressure between the end and intermediate parts of the pin and tube, at
- respectively opposite sides thereof, when the pin is inserted into the tube.
5. The combination with a strap having a loop in its end and a part having perforated lugs adapted to embrace such loop, of a tube adapted to occupy said loop and fit between said lugs with its bore in substantial 35 alignment with the perforations in the latter, and a pin adapted to be passed endwise by thrust exerted upon one end through such lugs and tube, said pin being resilient, and being in its normal unstressed condition so 40 far divergent as to the line in which it extends from the bore of said tube, that it is deflected from its normal shape by the walls of the tube and is caused to exert clutching pressure oppositely against said walls. 45
6. A connector for the purposes hereinbefore set forth consisting of a member having a bore and a pin adapted to be passed freely endwise through said bore, the pin and such bore being dissimilar in line to 50 such an extent that the pin, when contained in such bore, exerts resilient pressure against opposite walls thereof.

In testimony whereof I have affixed my signature.

EZRA C. FITCH.
